(57) CLAIM

I claim the ornamental design for a sport sliding board, as shown and described.

DESCRIPTION

FIG. 1 is an upper perspective view of the sport sliding board showing my design, portions of the board shown broken away for convenience of illustration;

FIG. 2 is a front view thereof;

FIG. 3 is a back view thereof;

FIG. 4 is a side view thereof;

FIG. 5 is an opposite side view thereof;

FIG. 6 is a top view thereof; and,

FIG. 7 is a bottom view thereof.
